WHIPSTOCK

Filed Sept. 10, 1941

UNITED STATES PATENT OFFICE

2,338,788

WHIPSTOCK

Clinton L. Walker, Piedmont, Calif.

Application September 10, 1941, Serial No. 410,259

5 Claims. (Cl. 255—1.6)

My invention relates to oil well drilling apparatus and particularly to a whipstock employed in the casing for producing deflection drilling.

In my Patent No. 2,132,061, issued October 4, 1938, I have illustrated a whipstock for producing deflection drilling over which the present whipstock is an improvement. The whipstock of the prior patent depended upon a pair of cables for lowering and raising the whipstock from the casing. Some objection was raised to the use of the cables for lowering and raising the whipstock because the cables tangled and failed to accurately orient the sloping surface of the whipstock relative to the direction in which the deflection drilling was to occur.

The whipstock embodied a block of metal having a sloping cam face and a conical mandrel which operated on a plurality of clutch plates for moving the clutch plates radially into engagement with the inner surface of the casing to lock the whipstock in position. The whipstock could be secured to the inner side of the casing at any point at which the deflection drilling was to occur. After the whipstock is set in position, a milling tool, mounted on the end of the drill stem, cut through the casing and drilling was continued through the opening in the casing in the usual manner.

The present invention pertains to an improved clutch construction and operating device therefore, which embodies a stem by which the whipstock is lowered in the casing and accurately oriented to have the cam surface face the direction in which the deflection drilling is to occur. The stem is thereafter released from the cam block, but continues to support a spindle which extends through the block and mandrel to support the clutch plates. The cam block drops and the mandrel forces the cam plates radially into the metal of the casing. A positive lock is thereby provided which prevents the whipstock from moving downwardly in the casing as the milling tool cuts through the casing wall.

After the completion of the drilling operation, the whipstock may be removed from the casing by the use of a stem which is guided into the central threaded opening of the cam block and screwed in position. When the stem is raised, the cam block, along with the conical mandrel, moves upwardly therewith, thereby releasing the clutch plates from the wall of the casing, permitting the whipstock to be drawn upwardly by the stem sections out of the top of the casing.

Accordingly, the main objects of my invention are: to provide a whipstock with a central threaded opening engageable by the end of a stem by which the whipstock is lowered and raised within the casing; to provide a series of clutch plates on the bottom of the whipstock which are attached to a plate on the end of the stem which

is supported thereby after the cam block is released therefrom; to provide a positive support for a series of radially movable cam plates which are moved outwardly by a tapered mandrel on the 5 end of a cam block, which is released from a supporting element to move the cam plates outwardly as they are supported against further movement downwardly in the casing; to provide a thread on the end of the spindle supporting the 10 plurality of clutch plates which is of finer pitch than the exterior threads on the supporting stem to permit the stem to be released from the cam block without releasing the spindle therefrom; to provide a drag spring on the end of the whipstock 15 of a strength sufficient to approximately support the whipstock within the casing; to provide a whipstock with a lowering device which accurately orients the whipstock and maintains the cam block spaced from the clutch plate and which 20 releases the cam block but supports the clutch plates when positioning the whipstock within a casing; to provide a whipstock which may be removed from the carrier by a supporting stem which engages the cam block portion for raising 25 the portion and releasing the clutch plates from engagement with the casing wall; and in general to provide a whipstock for the casing of a well which is accurately oriented and attached to the 30 wall of the casing and which may be removed therefrom.

Other objects and features of novelty of my invention will be specifically pointed out or will become apparent upon referring, for a better understanding of my invention, to the following description taken in conjunction with the accompanying drawing, wherein:

Fig. 1 is a sectional view of a well casing and a whipstock being lowered therein embodying features of my invention;

Fig. 2 is a view in elevation of the whipstock illustrated in Fig. 1;

Fig. 3 is a sectional view of the structure illustrated in Fig. 2, taken on the line 3—3 thereof;

Fig. 4 is a sectional view of the structure illustrated in Fig. 2, taken on the line 4—4 thereof;

Fig. 5 is a sectional view of the structure illustrated in Fig. 2, taken on the line 5—5 thereof; and

Fig. 6 is a view of structure, similar to that illustrated in Fig. 1, with the whipstock being raised from the casing after the well drilling operation.

In Fig. 1, I have illustrated a well casing 10 at a point from which deflection drilling is to take place. This may be necessary because of the loss of a string of tools, from a desire to deflect the bore from the original bore or for other reasons.

The whipstock embodying my invention comprises a cam block 11 having a sloping cam face 12 and a conical mandrel 13 on its lower end. A

central opening 14 is provided through the mandrel having a thread 15 which is engaged by a thread 16 on the outer surface of a supporting stem 17. Below the thread, the aperture 14 is reduced in diameter at 18 through which a spindle 19 projects having a thread 21 on its end which is of finer pitch than the thread 15. The thread 21 engages a similar thread 22 on the inner wall of the stem 17.

A key 23 is provided on the spindle 19 which prevents the spindle from rotating while permitting it to move a slight amount longitudinally of its length. The end of the spindle 19 contains a square end portion 24 on which a plate 25 is mounted supporting a plurality of studs 26 in slots 27. Each of the studs 26 is attached to a clutch plate 28 having an inner slotted tapered surface 29 which mates with the tapered conical surface of the mandrel 13. The mandrel is provided with projecting lands 31 which engage the slots in the surface 29 of the clutch plates 28. A drag spring 32 is supported on the square end portion 24 against the plate 25 by a nut 26.

The whipstock is supported on a plurality of stem sections 17 which are attached to each other as the whipstock is lowered into the casing 10. The whipstock is oriented, that is to say, 12 is positioned to have the sloping cam face 12 disposed in the direction in which the deflection drilling is to occur. Care is exercised as the additional sections of the stems 17 are attached and lowered to prevent the whipstock from changing its position so as to retain it oriented at all times.

After sufficient sections of the stem 17 have been added and lowered into the casing, the whipstock is positioned at a point where the deflection drilling is to occur. The drag 32 exerts sufficient pressure on the casing wall to permit the stem 17 to be screwed from the thread 15 without changing the position of the cam block 11. When the cam block 11 is released, the stem 17 continues to support the spindle 19 to which the clutch plates 28 are attached. The cam block 11 drops and the plates 28 are moved radially by the conical mandrel 13. A plurality of sharp longitudinal surfaces 33 on the outer faces of the clutch plates 28 are forced into the inner wall of the casing 10. This firmly clamps the whipstock in position within the casing, after which the stem 17 is released from the thread 21 on the end of the spindle 19 and is removed from the casing. A suitable cutter is then employed on the end of the drill stem for cutting through the wall of the casing, through which the deflection drilling occurs.

After the drilling operation has been completed, the whipstock may be removed by the stem 17, the endmost element 34 of which may be provided with a guide plate 35 having a thread 16 near the end from which a conical end portion 36 protrudes. The plate 35 and end 36 accurately guide the end of the element 34 into the aperture 14 in the cam block 11. After the thread 15 has engaged the thread 16 of the cam block, the cam block is raised along with the conical mandrel 13 which moves from engagement with the cam plates 28 which are free to shift radially inwardly out of contact with the inner wall of the casing 10.

After the cam plates are released, the whipstock may be drawn upwardly out of the casing. The use of the square end portion 24 of the spindle 19 prevents the drag spring 32 from

turning, thereby maintaining the whipstock 11 oriented at all times. The drag spring 32 also prevents the whipstock from turning when the stem 17 is unscrewed from the thread 15 of the cam plate 11. A slight longitudinal movement of the spindle 19 permits the turning of the stem 17 in the thread 15 while turning on the finer thread 21 of the spindle. The use of the splines 31 maintains the shoes 28 oriented relative to the mandrel 13 and all elements of the whipstock are maintained in operating relation to each other.

I claim as my invention:

1. A whipstock including in combination, a cam block having a clutch expanding mandrel, a spindle extending through said cam block and mandrel, a plurality of clutch plates supported for radial movement by said spindle, and a stem having threaded engagement with the cam block and spindle, the threads being such as to permit the disengagement of the stem from the cam block while maintaining the spindle secured thereto.

2. A whipstock including in combination, a cam block having a clutch expanding mandrel, a spindle extending through said cam block and mandrel, a plurality of clutch plates supported for radial movement by said spindle, a stem having threaded engagement with the cam block and spindle, the threads being such as to permit the disengagement of the stem from the cam block while maintaining the spindle secured thereto, a drag spring on the lower end of the spindle, and means for retaining said drag spring from turning relative to said spindle.

3. The combination in a whipstock, of a cam block having a sloping cam surface, a clutch expanding mandrel on the lower end of said cam block, a spindle extending through said mandrel and cam block and retained against rotation relative thereto, a plate supported by said spindle, a plurality of cam plates supported by said spindle plate for radial movement, means for maintaining said cam plates and mandrel against relative rotation, and a drag spring mounted on the end of said spindle.

4. The combination in a whipstock, of a cam block having a sloping cam surface, a clutch expanding mandrel on the lower end of said cam block, a spindle extending through said mandrel and cam block and retained against rotation relative thereto, a plate supported by said spindle, a plurality of cam plates supported by said spindle plate for radial movement, means for maintaining said cam plates and mandrel against relative rotation, a drag spring mounted on the end of said spindle, and a stem independently secured to the cam block and spindle in such manner as to be releasable from the former without being separated from the latter.

5. The combination in a whipstock, of a cam block having a sloping cam surface, a clutch expanding mandrel on the lower end of said cam block, a spindle extending through said mandrel and cam block and retained against rotation relative thereto, a plate supported by said spindle, a plurality of cam plates supported by said spindle plate for radial movement, means for maintaining said cam plates and mandrel against relative rotation, a drag spring mounted on the end of said spindle, and a stem for engaging the cam block and collapsing the cam plates when raising the whipstock.

CLINTON L. WALKER.
